J. LE R. BANKS

RECORDING MACHINE

Original Filed July 22, 1924

UNITED STATES PATENT OFFICE.

JOSEPH LE ROY BANKS, OF BALTIMORE, MARYLAND, ASSIGNOR TO THE BOLMONICA
MUSIC CO., OF BALTIMORE, MARYLAND.

RECORDING MACHINE.

Application filed July 22, 1924, Serial No. 727,467. Renewed November 15, 1927.

My invention relates to recording machines such as are used for making perforated sheet rolls for notes controlling means for musical instruments or their master 5 sheets for duplication of the former; for type setting machines, type casting machines, etc., through the perforation of which air is either forced or drawn to either operate or control the operation of the tones of musical instruments, etc.; or through which the operation 10 or control of the operation of type setting, or type casting machines, etc., is effected; or the control or the operation of other perforating or punching, marking, or printing machines is effected. 15

The objects are first, to provide a new article of manufacture;

2nd. To provide a new machine for perforating, punching, marking, or printing materials; 20

3rd. To provide a machine for perforating, punching, marking, or printing materials, operated by electric means.

4th. To provide a machine for perforat-

25 ing, punching, marking, or printing, operated by pneumatic and electric means.

5th. To provide a machine for perforating, punching, marking, or printing by play-

30 ing upon the wind instrument.

6th. To provide a machine for perforating, punching, marking, or printing, by playing upon a wind musical instrument and utilizing the same air or wind which operates the musical tones to operate the machine.

35 7th. To provide an electrically operated machine for perforating, punching, marking, or printing.

8th. To provide a pneumatically operated machine for perforating, punching, marking, or printing.

40 To these ends, I provide musical instruments or other wind instruments as they may be termed, with nipples and pneumatic flexible tubes leading from the tones producing devices, or from the passageways leading to the tones, or from the same, producing devices, to devices operable by pneumatic

means, carrying means for perforating marking, or printing materials while the materials are moved under and past the perforating, 50 marking, punching, or printing devices at the proper rate of speed.

My machine also provides means operable by pneumatic means controlled by pneumatic tubes leading from wind instruments, where- 55 by perforating, punching, marking, or printing devices are operated.

Instead of musical instruments, I may use a device without tones producing means and having the passageways or tubes marked 60 with numerals, or letters, or characters.

It is obvious that a pencil or other marking device may be substituted in place of the punch; and likewise a stencil printing device or other printing device may be substituted 65 for the punch without changing the machine except to close up the holes in the die.

It is obvious also that a carbon sheet may be placed on top of the materials to be marked or printed and moved with the said 70 materials in the machine.

Referring to the drawings—

Fig. 1 is a sectional side elevation of my machine.

Fig. 2 is a side elevation of my electrical 75 tappet lever or key showing the reversal of the contact points for closing the electrical circuit.

Fig. 3 is a view looking from the bottom of my machine. 80

Referring to the numerals,—
1 is the leg of the bed 2' through which the wires 6 and 7 attached to the electrodes 2 and 3 pass in their respective holes 4 and 5 to the helix 52 of the electric magnet with its core 53 and respectively to the binding nuts 9 and 10.

The wire 7 secured by the binding nuts 9 and 10 is in contact with the terminal bracket 8 carrying the contact 17, and the bracket 8 90 is supported upon the insulating post 11 by the nuts 9 and 9'.

Below this bracket 8 is another adjustable bracket 15 carrying the rest 14 and is secured

to the insulating post 11 by the nuts 15' and 15", and the insulating post 11 is secured to the bed 2' by the nuts 12 and 13.

Between the two brackets 8 and 15 is the electric lever 18 resting upon the insulating diaphragm 20 of rubber or other flexible material, and carrying the contact point 16 at one end, and at the other end 28 is hinged by the pin 31 in the support 31' held by the bolt 32 passing through the insulating bushing 33 and the insulating washer 34 and insulating washer 34' and threaded into the nut 35.

This diaphragm 20 is secured by a ring or tube 25 on the inside of the diaphragm 20 pressing it against the receptacle 21 held onto the bed 2' by the screws 24 and 22 passing through the flange 23 of the receptacle.

19 is the chamber of the diaphragm 20 which leads out of the nipple 26 through the outlet 29, and to the nipple 26 is secured the flexible tubing 27 connected at its other end 69 over the nipple 63 secured to the wind musical instrument 61 by the reed block 67.

66 is the wind chest of the musical instrument 61.

62 is the air passageway to the tones device or the reed 65 secured upon the reed plate 64.

70—71—72—73—74—75—76—77 are nipples secured to mate with individual air passageways in the reed block 67 for operating other tones producing devices or reeds and to which nipples other flexible tubes may be attached to operate other electric lever keys for operating circuits by connecting the tubes in similar manner as before to other diaphragms operating levers with contact points or circuit makers to operate other electromagnets and punches.

The electromagnet 53 is secured to the bed 2' by the bolt 53'.

55' is the standard secured to the bed 2' and in which is pivoted the tappet lever armature 54 by the pin 55.

This tappet lever armature is normally held away from the electro magnet 53 by the spring 56 secured to the standard 55 by the bolt 57, and the punch 51 slidably mounted in the standard 50 secured onto the bed 2' by the bolt 47.

50 This punch 51 is provided with a pin 49 resting upon a spring 48 secured to the standard 50 by the bolt 48' and by which spring 48 the punch 51 is held in a normal position for operating it.

55 Below the bed 2' are suitably secured the feed rollers 40 and 36, and 41 and 37 between which pairs the paper 100 or other material to be punched passes from one reel 42 to the other reel 39.

60 The reel 42 is supported by the hanger 85 secured by the bolt 59 to the leg 58 of the bed 2', and is rotated by the spindle 43 secured to the crank 44. The reel 39 is revolved by the spindle 39', in the hanger 38, attached to the crank 60.

The die plate 46 is secured by the bolt 46' to the bed 2' and is so arranged that the material 100 passes between the die plate 46 and the bed 2' and between the feed rollers 36 and 40, and 41 and 37.

80 is a bracket for supporting the bearings for the feed rollers and 38 is the hanger for the reel 39 in which the spindle 39' is inserted, and both the bracket 80 and the hanger 38 are secured to the bed 2' by the bolts 78 and 82.

45 is the hole in the die 46 through which the perforations are made by the punch 51.

44 is the crank secured to the spindle 43 by which the reel 42 is turned.

22 is the head of the bolt 30.

81 is a bracket attached to the hanger 80' which is secured by the bolts 78 and 82 to the bed 2'.

84 is a bolt for securing the opposite hanger 83 to the leg 58 of the bed 2'.

In operating the perforating or punching machine by the wind instrument, the wind instrument is played upon by suitable means and the air operating the tones will also expand the diaphragm 20 by increasing the pressure under the diaphragm 20 in the chamber 19 thereby raising the diaphragm and the lever 18 resting upon it and closing the contact points 16 and 17 makes the circuit to the electromagnet 52—53, and effecting the operation of the armature lever 54 which drives the punch 51 through the paper material 100.

In Figure 2 the lever 18 is arranged with the contact 16 on the reverse side and the contact bracket 8 is reversed and arranged below the lever contact point 16, so that when air is drawn from under the diaphragm 20 decreasing the pressure under it, the diaphragm 20 will fall sufficiently to permit the lever 18 to drop and make contact with the contact points 16 and 17 thereby closing the circuit from the battery 3' to the electromagnet 52—53; this latter arrangement is used when the tones are produced by suction to also operate the punches 51.

I do not care to limit myself to any particular design or construction except as defined by my claims.

Instead of punching the sheet materials, I may simply mark the paper or other material by substituting a marking device for the punch 51. Or I may substitute a printing device for the punch 51. It is obvious that if a substitution of a printing or other marking device for the punch is made, the holes in the die plate will be closed.

What I claim is—

1. A recording machine comprising an air chamber and a diaphragm secured over said chamber, said chamber being provided with an inlet with means for attaching a tube to said inlet, electrical contacts provided with

means for supporting them over said diaphragm, means for operating said diaphragm to manipulate said electrical contacts, said contacts controlling electrical circuit to an 6 electro-magnet, recording means operable by said electro-magnet, and means for receiving the record.

2. A recording machine comprising a plurality of air chambers provided with diaphragms and inlets to each chamber with means for varying the pressure in each chamber to operate said diaphragms, electrical contacts with means for supporting them over their respective diaphragms, electric 15 circuits secured to said contacts and to the helices of electro-magnets respectively, said electro-magnets provided with means for operating recording devices, recording devices operable by said electro-magnets respectively, and means for receiving the record.

3. A recording machine comprising a plurality of air-chambers provided with diaphragms and inlets to each chamber, one 25 series of diaphragms operable by increasing the air pressure in said chambers, and another series of diaphragms operable by diminishing the air pressure in their respective chambers, electrical contacts provided with 30 means for supporting them over said diaphragms respectively, electric circuits secured to said contacts respectively and to electro-magnets respectively, said electro-magnets provided with means for operating 35 recording devices, recording devices operable by said electro-magnets respectively, means for receiving the record and means for moving the record.

4. In a recording machine, a musical instrument provided with means for conveying air currents to produce the musical sounds and also provided with means for branching the air currents to operate means for operating recording means.

5. A recording machine set forth in claim 2 and provided with means for rolling up the record.

6. A recording machine comprising a musical instrument provided with a plurality of air-current controls, each of said air-current controls provided with an outlet, a plurality of air chambers, means secured to said outlets and to said chambers respectively for connecting said controls to said 55 chambers respectively, said chambers provided with means for securing said connecting means and also provided with diaphragms for operating electrical circuits, electrical circuits operable by said diaphragms respectively, and recording devices operable by said electrical circuits respectively.

7. A recording machine comprising a harmonica provided with a plurality of air-current passageways provided with outlets

and a series of sound producing means secured in the usual manner of harmonicas, a plurality of air chambers and a plurality of means for connecting said outlets to said chambers respectively, said chambers provided with diaphragms for operating electric circuits respectively, electrical circuits operable by said diaphragms respectively for controlling the operation of recording devices respectively, and a plurality of recording devices operable by said electrical circuits respectively.

8. A recording machine comprising a musical instrument provided with a plurality of air-current controls for controlling the sounds of said musical instrument, a plurality of nipples secured to said controls respectively, passageways through said nipples into said controls, and a plurality of air chambers each provided with a nipple respectively, a tube suitably secured to each nipple of said controls and said chambers respectively, each of said chambers provided with diaphragms for operating electrical circuits respectively, electrical circuits operable by said diaphragms respectively and a plurality of recording devices operable by said electrical circuits respectively.

9. A recording machine comprising a musical instrument provided with a plurality of air-current controls for controlling the sounds of said musical instrument, a plurality of nipples secured to said controls respectively, passageways into said controls through said nipples, and a plurality of air chambers each provided with a nipple provided with a passageway leading into said chambers respectively, a flexible tube suitably secured to each nipple of said controls and each nipple of said chambers respectively, each of said chambers provided with diaphragms for operating electrical circuits respectively, electrical circuits operable by said diaphragms respectively for controlling the operation of recording devices respectively, and a plurality of recording devices operable by said electrical circuits respectively.

10. A recording machine comprising a musical instrument provided with a plurality of air-current controls for controlling the sounds of said musical instrument respectively, a plurality of nipples secured to said controls respectively, passageways through said nipples into said controls, and a plurality of air chambers each provided with a nipple having a passageway into said chambers respectively, a plurality of tubes detachably secured at opposite ends to said nipples respectively of said controls and said nipples respectively of said chambers, said chambers provided with diaphragms respectively for controlling electrical circuits respectively, electrical circuits operable by said diaphragms respectively, and a plurality of

recording devices operable by said electrical circuits respectively.

11. A recording device comprising in combination, a musical instrument having passages therein, through which air is adapted to pass to sound a note, an air chamber connected to said passageway, said chamber

having a pressure responsive diaphragm, a contact movable under impulse of said diaphragm, an electric magnet in circuit with said contact, and recording means operated by said magnet. 10

JOSEPH LE ROY BANKS.
